UNITED STATES PATENT OFFICE

2,506,010

ELECTRICAL CONNECTOR CLAMP

Theodore Birkenmaier, St. Louis, Mo., assignor
to W. N. Matthews Corporation, St. Louis, Mo.,
a corporation of Missouri

Application March 12, 1947, Serial No. 734,098

3 Claims. (Cl. 173—273)

1

This invention relates to electrical connector clamps and, more particularly, to clamp devices of this class for electrically connecting a tap-off wire to a line wire.

Among the several objects of the invention may be noted the provision of an electrical connector embodying an improved clamp for readily effecting electrical connection between a tap-off wire and a line wire; the provision of a connector of the class described adapted easily to be applied and firmly attached to a line wire by means of the usual clamp stick; the provision of a connector of this class adapted to remain securely clamped in electrical conductive relation to the line wire despite vibration or other factors tending to loosen the clamp, yet which is easily removed from the line wire when so desired; and the provision of a connector such as described which is easy and economical to manufacture. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a side elevation of the electrical connector of this invention;

Fig. 2 is an end elevation thereof as viewed from the right of Fig. 1; and,

Fig. 3 is a view similar to Fig. 1, but partly in section and illustrating the clamp applied to a line wire.

Similar reference characters indicate corresponding parts throughout the several views of the drawings.

Referring to the drawing, there is generally shown at 1 a clamp body comprising a web portion 3 and a flange 5. The clamp body is provided with a jaw 7 formed with a recess 9 shaped to accommodate a line wire A (Fig. 3). The web 3 of the clamp body carries wire-connector means 11 of any suitable construction for attaching a tap-off wire B thereto. As illustrated herein, means 11 comprises a split bolt 13 carried by the web 3 and having a nut 15 threaded thereon adapted to be screwed up on the bolt to clamp the tap-off wire in electrical conductive relation to the web.

Spaced wall flanges 17 and 19 extend outward from the end of the clamp body opposite the

jaw 7 generally at right angles to the flange 5. The outer ends of flanges 17 and 19 are preferably, though not necessarily, joined by a web 21 to strengthen the construction. A lock nut 23, of a special construction to be described, is non-rotatably received in the recess or compartment 25 between flanges 17 and 19. This lock nut is threaded on a clamp bolt 27, the latter extending freely through unthreaded apertures 29 and 31 in flanges or buttresses 17 and 19.

The clamp bolt 27, on its upper end adjacent jaw 7, carries a jaw 33 cooperating with jaw 7 for clamping the line wire A therebetween. Jaw 33 is formed with a recess 35 shaped to accommodate the line wire A. The upper end of the bolt 27 is rotatable in the jaw 33 but is fixed against axial movement with respect thereto by means of a pin 37 fixed in the jaw and traversing a groove 39 in the end of the bolt. The jaw 33 is prevented from rotation by engagement of the side 41 thereof with flange 5 of the clamp body, and also by engagement of ears 43 thereon with the edges of flange 5. Ears 43 also cooperate with the edges of flange 5 to guide the jaw 33 in its movement toward and away from jaw 7. The lower end of the bolt is formed as an eye 45 to receive a hook on the end of a clamp stick for turning the bolt.

The lock nut 23 comprises a generally rectangular nut, preferably formed of a lubricant-bearing metal, such as an oil-bearing compressed powdered and sintered metal. This nut is transversely slotted, as indicated at 47, to provide two transverse tongues 49 connected by a base portion 51. Rotation of the nut is prevented by engagement of a flat side thereof either with flange 5 of the clamp body or with web 21. Flanges 17 and 19 function as stops to limit axial movement of the nut.

The inside surface 53 of the lower flange 19 (its surface within the nut receiving recess 25) is inclined with respect to the normal plane of the lower surface of the nut, as illustrated in Fig. 1. The nut is received in recess 25 with the tongues 49 extending toward the high side of this inclined surface. While as illustrated herein, the tongues extend outward from the flange 5 and the surface 53 inclines upward away from flange 19, it will be apparent that this relation may be reversed. It will also be apparent that the tongues may extend parallel to the flange, instead of transversely with respect thereto, in which case the surface 53 will again be inclined upward toward the free end of the tongues. It will be further apparent that the inside surface of the

2

flange 19 could be perpendicular to the flange 5 and the lower surface of the nut 23 may be inclined. Other alternatives will readily suggest themselves.

The web 3 of the clamp body has an aperture 55 therein for receiving the hook of a clamp stick. In employing the clamp of this invention to make a connection between the tap-off wire and a line wire, the procedure is as follows:

The clamp bolt 27 is turned to retract jaw 33 until it is spaced a sufficient distance from jaw 7 to permit the clamp to be applied over a line wire A. The tap-off wire B is clamped to the clamp body 1 by the means 11. The hook of a clamp stick (not shown) is inserted in aperture 55 and the stick employed to raise the clamp and engage jaw 7 over the line wire. Upon removal of the hook of the clamp stick from aperture 55, the clamp is suspended on the line wire A, recess 9 in jaw 7 accommodating the line wire.

The hook of the clamp stick is then inserted in the eye 45 of the bolt and manipulated to turn the bolt to move jaw 33 toward jaw 7 so as to clamp the wire between these jaws. During this operation, the bolt turns easily in the nut 23. Rotation of the nut is prevented by means of engagement of a flat side thereof either with flange 5 or strut 21, so that turning of the bolt effects axial movement of the bolt.

When the bolt has been turned sufficiently to cause jaw 33 to exert clamping force on the line wire A, as illustrated in Fig. 3, further upward axial movement of the bolt is prevented. Further turning of the bolt, while it does not result in axial movement of the bolt, causes the nut 23 to travel downward into pressure engagement with the inclined thrust surface 53. This distorts the nut, causing the lower tongue 49 to become canted toward the upper tongue, as illustrated in Fig. 3. Some looseness in the threads favors distortion. This causes the threads of the nut to bind on the bolt threads, thereby releasably to lock the nut to the bolt to maintain the line wire A tightly clamped between the jaws 7 and 33 despite vibration or other factors which tend to loosen the nut.

The clamp may be readily removed from the line wire A, if so desired, by turning the bolt with the clamp stick to retract jaw 33. While considerable force must be initially exerted to turn the bolt to unlock nut 23, the amount of force required is not unreasonable. When the bolt is initially turned, the nut 23 travels upward away from engagement with the inclined thrust surface 53 and tongues 49 return to their normal parallel relation illustrated in Fig. 1, due to the resilience of the portions of the nut connecting its base portion 51 and the tongues. After the nut has been thus unlocked, the bolt may be turned easily because the induced distortion is not beyond the elastic limit. The nut is preferably made of the aforesaid lubricant-bearing metal which provides for convenient constant lubrication of the threads so that the bolt may be turned in the nut without requiring unreasonable force, even after the clamp has been applied to a line wire in an exposed location for a considerable period of time.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. An electrical connector comprising a clamp body having a jaw thereon and an aperture therein adapted to receive the hook of a clamp stick, means for attaching a tap-off wire to the clamp body, a bolt mounted for axial movement in a pair of spaced flanges which extend outward from the clamp body, said bolt carrying at one end a jaw cooperable with the jaw on the clamp body for clamping a line wire therebetween, the other end of the bolt being formed as an eye to receive the hook of a clamp stick, a nut non-rotatably mounted in the recess between said flanges but adapted for limited axial movement therein, said nut being threaded on said bolt, said nut being transversely slit to form two spaced tongues, the inner surface of the flange remote from the jaw-carrying end of said bolt being inclined to the adjacent surface of the end of the nut when the bolt is retracted to separate said jaws.

2. An electrical connector as set forth in claim 1, wherein the nut is formed of a lubricant-bearing material.

3. An electrical connector comprising a clamp body having a jaw, a tap-off wire connector carried by the clamp body, a bolt carried by the clamp body for rotation and for axial movement toward and away from the jaw on the clamp body, a jaw rotary on the end of the bolt opposed to the jaw on the clamp body for clamping a line wire therebetween, when the bolt is moved toward the jaw on the clamp body, said jaw on the bolt having sliding, non-rotary engagement with the clamp body, a nut formed of lubricant-bearing material having a transverse slot to form two spaced tongues threaded on the bolt and located between the jaw on the bolt and the other end of the bolt, said clamp body being formed with portions engageable with the nut for preventing rotation thereof and for limiting axial movement thereof and adapted to cause one of the tongues to cant toward the other when the bolt is turned to clamp a line wire between the jaws, thereby releasably locking the nut on the bolt.
